Primary Examiner — Cynthia Underwood*(74) Attorney, Agent, or Firm* — Stetina Brunda Garred & Brucker(57) CLAIM

The ornamental design for a bracelet type purse hanger, as shown and described.

DESCRIPTION

FIG. 1 is a perspective view of the bracelet type purse hanger of the present invention showing my new design;

FIG. 2 is a front elevational view thereof;

FIG. 3 is a left side view thereof;

FIG. 4 is a top plan view thereof;

FIG. 5 is a right end view thereof;

FIG. 6 is a rear elevational view thereof;

FIG. 7 is a bottom plan view thereof; and,

FIG. 8 is front elevational view thereof depicting the bracelet type purse hanger in its open configuration, with the dotted lines depicting solely environmental structure and forming no part of the claimed design.

1 Claim, 3 Drawing Sheets(56)
